UNITED STATES PATENT OFFICE.

WILLIAM FRIEDMAN, OF NEW YORK, N. Y., ASSIGNOR TO JOHN W. ARNOLD, DAN H. ARNOLD, ADELAIDE F. ARNOLD, AND MILDRED C. ARNOLD, COPARTNERS DOING BUSINESS AS F. R. ARNOLD & COMPANY, OF NEW YORK, N. Y.

TOILET PACKET.

Application filed November 5, 1925. Serial No. 66,933.

To all whom it may concern:

Be it known that I, WILLIAM FRIEDMAN, citizen of the United States, residing at New York city, N. Y., have invented certain new and useful Improvements in Toilet Packets; and I do hereby declare the following to be a full, clear, and exact description of the invention, such as will enable others skilled in the art to which it appertains to make and use the same.

The object of this invention is to provide a compact, inexpensive toilet packet of handy size and shape, convenient to use, sanitary, and of continued utility for a considerable time, and in which are included toilet accessory units having toilet preparation thereon and which have to be removed from the article or packet for use and be thrown away after use, such packet comprising a strip or strips made up of such units which are separable from the strip by tearing individually therefrom; to provide also where desired a covered packet of this character containing toilet accessory units of different kinds all equally accessible on opening the cover; to secure simplicity of construction, economy of manufacture, increased utility and desirability of the article, and to obtain other advantages and results as may be brought out in the following description.

Referring to the accompanying drawing in which like numerals of reference indicate similar parts throughout the several views, Figure 1 is a perspective view of a packet embodying my invention in open position for disclosing all of the component parts thereof;

Figures 2 and 3 are side or edge views showing the protective covering in different positions; and

Figure 4 is a perspective view of a slightly modified construction of packet.

In the specific embodiment of the invention illustrated in said drawing, and particularly in Figures 1-3, the reference numeral 1 indicates the protective covering which may be made of a strip of cardboard or the like which is preferably transversely doubled at two separate places, as at 2 and 3, so as to provide three cover sections 4, 5 and 6. For convenience, these sections will be referred to as front cover 4, back cover 5 and loose or insert end 6. The several parts in-

cluded within the cover are held together by a staple 7 which passes through the front cover 4 and back cover 5 adjacent the bend 2 in the strip forming the covering. By this structure, the back cover 5 and loose or insert end 6 constitute a long strip together substantially twice as long as the front cover 4.

Secured to the cover and included between its front and back is a strip of unitary devices 8 which are preferably sub-strips forming part of a subdivided strip of cardboard and each of which is provided on its outer end with a toilet accessory tip 9, of cosmetic or other toilet preparation, sufficient for a single or individual use so that each time one of the sub-strips is torn out and one of the tips used the sub-strip can and will be thrown away and the next time cosmetic is desired, another sub-strip will be used until they are all gone. Within the covering and secured thereto is preferably included also a strip of paper or the like 10 having sub-strips on each of which is carried a sufficient amount of powder for individual use. These individual strips or powder sticks will also be torn out for use and each thrown away after it has been used. Neither the term "sub-divided" applied to the strip of unitary devices 8 nor the term "sub-strip" applied to the said devices and to the individual powder sticks implies that adjacent strips must necessarily be in contact and not spaced apart. Within the covering is also a pad 11 providing a paper of suitable texture for wiping purposes, as for spreading or removing the cosmetics or for such other purposes as the user may find desirable. This paper may likewise be impregnated with powder, perfume or other material which will add to its utility or desirability. The paper comprising this pad likewise will provide advertising space and also space for making notes or for writing upon as best meets the needs or demands of the user.

In order to make the article complete as a make-up kit, a reflecting surface is provided in the packet. As shown in Figure 1, this reflecting surface 12 is carried as the end leaf of the pad, that is, between the back of the pad and the powder sticks. The exact arrangement of the several parts within the packet may be varied, and in Figure 4 I have shown a reflecting surface 13 on the

inside of the back cover 14 and insert end 15. In this figure, I also have shown the front end 16 of the covering as cut off adjacent the staple 17 and have shown the 5 powder sticks 18 forming the top layer, cosmetic sticks 19 positioned immediately thereunder and a pad 20 beneath the cosmetics and between said cosmetics and the said back cover.

10 It will be understood that in use the insert end 6 of the covering may be drawn out as in Figure 1 and the several individual articles contained within the covering may be used as best fits the desire, needs 15 or whims of the lady, and the individual units which are used are then thrown away and the insert end returned to its position as shown in Figure 2 between the pad and the front cover. If preferred, however, the 20 insert end may be introduced between the pad and the strip of powder sticks as shown in Figure 3 so as to provide a pad with its cover 4 and backing of the remaining portions of the covering and contents, the pad 25 then being convenient for reference and properly reinforced for writing notes upon.

Obviously detail changes and modifications may be made in the construction and use of my improved packet, and I do not 30 wish to be understood as limiting myself to the precise units specified there as to size, shape or materials or order in which they are included, except as set forth in the following claims when construed in the light of 35 the prior art.

Having thus described the invention, I claim:—

1. A unitary article of manufacture comprising a subdivided strip of units bearing 40 toilet-preparation and adapted for individual use by tearing the individual units from

the strip, and a protective covering for said strip.

2. A unitary article of manufacture comprising a strip of cosmetic units adapted for 45 individual use by tearing the individual units from the strip, and individual powder carriers attached thereto and adapted to be used by tearing them from the article.

3. A unitary article of manufacture comprising a strip of cosmetic units adapted for 50 individual use by tearing the individual units from the strip, and individual powder carriers attached thereto and adapted to be used by tearing them from the article, and 55 a cover for said parts.

4. A toilet packet comprising a strip of units united together and separable by tearing one from the others, said units having 60 toilet accessory tips, whereby each unit may be utilized individually and thrown away after use.

5. A toilet packet comprising a strip of cardboard slit inwardly from one edge less than the distance to the opposite edge so as 65 to provide a plurality of units integral with each other at their corresponding ends and removable for use by tearing one from the others thus enabling each unit to be used only once, and a toilet preparation on each 70 unit for individual use.

6. A toilet packet comprising a strip of fibrous material made up of sub-units, each carrying toilet preparation at one end and adapted to be torn from the strip for individual use, and a flexible cover secured to that edge of the strip which is free from 75 toilet preparation and having its free end adapted to enfold the free edge of the strip and be releasably secured to the packet.

WILLIAM FRIEDMAN.
